(57) **CLAIM**

I claim the ornamental design for the soda float device, as
shown and described.

DESCRIPTION

FIG. 1 is a perspective view of my new soda float device
installed on a soft drink bottle;

FIG. 2 is a front side elevational view thereof;

FIG. 3 is a top view thereof;

FIG. 4 is a right side elevational view thereof;

FIG. 5 is a left side elevational view thereof;

FIG. 6 is a back side elevational view thereof;

FIG. 7 is a bottom view thereof;

FIG. 8 is an exploded front side elevational view thereof;

FIG. 9 is an upward looking inside view of the lid portion
thereof;

FIG. 10 is a top view of the reservoir portion thereof;

FIG. 11 is a partially cut away front side elevational view
thereof;

FIG. 12 is a left side cross-sectional view thereof taken along
the line 12-12; and,

FIG. 13 is a perspective exploded view thereof illustrating a
shrink wrap coating on the reservoir portion.

The broken lines in the drawings depict environmental sub-
ject matter only and form no part of the claimed design.
